CIRCUIT INTERRUPTER.

1,427,367.

Specification of Letters Patent. Patented Aug. 29, 1922.

Application filed October 17, 1918. Serial No. 258,554.

To all whom it may concern:

Be it known that we, CHARLES LE G. FORTESCUE, a subject of the King of Great Britain, and a resident of Pittsburgh, in the county of Allegheny and State of Pennsylvania, and FREDERIC C. HANKER, a citizen of the United States, and a resident of Wilkinsburg, in the county of Allegheny and State of Pennsylvania, have invented a new and useful Improvement in Circuit Interrupters, of which the following is a specification.

Our invention relates to circuit interrupters and particularly to quick-acting interrupters.

One object of our invention is to provide means for interrupting a circuit in anticipation of an overload thereon.

Another object of our invention is to provide a circuit-interrupter-actuating device that shall be so controlled directly from the circuit that its time of operation shall be relatively short.

A further object of our invention is to provide a circuit-interrupting device, of the above-indicated character, that shall be simple and inexpensive to construct and accurate in its operation.

In practicing our invention we provide a circuit interrupter and an electromagnet comprising a stationary core member having an air gap therein, an armature that normally bridges the air gap and is operatively connected to the circuit interrupter, a spring for actuating the armature to its open position, a winding for so energizing the stationary core member as to normally hold the armature in its closed position, and a winding operatively connected to the circuit and so disposed with respect to the armature that, when the current in the direct-current circuit changes quickly, by reason of a ground or short circuit thereon, sufficient current will be induced in the winding to divert the flux from the armature through the air gap in the stationary core member and thus permit the spring to quickly open the interrupter. Since the impulse current that is set up is caused by the rapid change in current incident to a ground or short circuit on the system, the interrupter may be opened in anticipation of an actual overload on the circuit.

The single figure of the accompanying

drawing is a diagrammatic view of a direct-current circuit embodying our invention.

A direct-current circuit 1 is supplied with energy from a source 2 of electromotive force and is provided with a circuit interrupter 3 having an actuating and controlling device 4.

A device 4 comprises a stationary magnetizable core member 5 of substantially rectangular shape having an air gap 6 in one leg thereof, an armature 8 that is pivotally mounted, at a point 9 on the core member 5, and an actuating winding 7 that is connected in shunt relation to the circuit 1 for actuating the armature 8 to such position as to open the interrupter 3 under predetermined conditions. A winding 12 is disposed around the armature 8, and is connected, through a resistor 13, to the terminals of a series transformer 14 with which the circuit 1 is provided.

Since the armature 8 is adapted to bridge the air gap 6 under normal conditions, the flux set up by the winding 7 will traverse the armature 8 and three legs of the core member 5 to thereby hold the interrupter 3 in its closed position. When a short circuit or ground occurs on the circuit 1, the voltage of the circuit will change quickly and thereby induce voltage in the transformer 14 that will cause sufficient current to traverse the winding 12 to set up a flux in opposition to the flux set up in the armature 8 by the winding 7. Since the current traversing the winding 12 prevents the flux set up by the winding 7 from traversing the armature 8, this flux will be diverted through the leg 15 of the core member 5 and across the air gap 6 and thus permit the spring 11 to quickly move the armature and, consequently, the circuit interrupter 3, to open position.

It will be understood that the function of the winding 12 is not to neutralize the flux set up by the winding 7, but merely to so divert the same through another path that the time of operation of the interrupter will be reduced to a minimum value. It will further be understood that the winding 12 is so quickly energized, by reason of the quick change in voltage when a fault obtains on the circuit 1, that the interrupter 3 may be opened substantially in anticipation of an actual overload on the circuit.

Our invention is not limited to the par-

ticular structures or arrangement illustrated, as it may be variously modified without departing from the spirit and scope of the invention, as set forth in the appended claims.

5 We claim as our invention:

1. In a direct-current circuit, the combination with a circuit interrupter, of electromagnetic means for holding the interrupter closed, and means dependent only upon a quick change of current in the circuit for so shifting the flux of the electromagnetic means that the interrupter is quickly opened.
- 10 2. In a direct-current circuit, the combination with a circuit interrupter, of an electromagnetic device energized by a potential winding for holding the interrupter closed, and means energized from the circuit only upon a quick change of current in the circuit for so shifting the flux of the electromagnetic device that the interrupter is permitted to open quickly.
- 15 3. In a direct-current circuit, the combination with a circuit interrupter, of an electromagnet having two parallel magnetic paths adapted to hold the interrupter in its closed position, and means dependent upon the rate of change of current in the circuit and associated with one of the paths for causing the flux to traverse the other path.
- 20 4. In an electric circuit, the combination with a circuit interrupter, of an electromagnet comprising a stationary magnetizable core member, an armature, a potential winding for actuating the armature to hold the interrupter closed, and a winding energized (in anticipation) of a rush of current in the circuit for preventing the flux from the potential winding from actuating the armature.
- 25 5. The combination with a circuit interrupter, of an electromagnet having a partially closed magnetic circuit, an armature normally completing the magnetic circuit for holding the interrupter closed, means for energizing the electromagnet, and means energized upon a relatively quick change in the current in the interrupter to prevent the flux set up by the energizing means from traversing the armature.
- 30 6. The combination with a circuit interrupter, of an electromagnet comprising a core member having an air gap therein, an armature normally bridging the air gap for holding the interrupter in its closed position, a winding for energizing the electromagnet, and a winding disposed around the armature to oppose the flow of magnetic lines therethrough from the core member only when a sudden overload traverses the interrupter.
- 35 7. In an electric circuit, the combination with a circuit interrupter, of an electromagnet having a potential winding operatively connected to the circuit for holding the interrupter closed, and means operatively connected to the circuit and dependent upon the change of current in the circuit, for demagnetizing a portion of the electromagnet.
- 40 8. In an electric circuit, the combination with a circuit interrupter, of an electromagnet comprising an armature for directly actuating the interrupter, a potential winding for actuating the armature, and means dependent upon the rate of change of current in the circuit, for rendering the armature non-responsive to the potential winding.
- 45 9. In an electric circuit, the combination with a circuit interrupter, of an electromagnet comprising an armature for directly actuating the interrupter, a potential winding for actuating the armature in one direction, a spring for actuating the armature in the other direction, and means dependent upon the rate of change of current in the circuit, for rendering the armature non-responsive to the potential winding.
- 50 10. In an electric circuit, the combination with a circuit interrupter, of an electromagnet comprising an armature for directly actuating the interrupter, a potential winding for actuating the armature in one direction, a spring for actuating the armature in the other direction, and means for rendering the armature non-responsive to the potential winding only when the current traversing the circuit increases quickly.
- 55 11. In a direct-current circuit, the combination with a circuit interrupter, of an electromagnet comprising an armature for holding the interrupter closed, a spring for opening the interrupter, a winding for actuating the armature to its closed position, and a winding adapted to be energized from the circuit only when the current traversing the circuit changes quickly to so demagnetize the armature as to permit the spring to open the interrupter quickly.
- 60 12. In an electric circuit, the combination with a circuit interrupter, of an electromagnet comprising a core member and an armature member, means for energizing the core member and means disposed around the armature member for deflecting the magnetic flux therefrom in anticipation of a sudden overload on the circuit.
- 65 13. In an electric circuit, the combination with a circuit interrupter, of an electromagnet for holding the interrupter closed, and means dependent upon the rate of change in the condition of the circuit for so decreasing the holding effect of the flux of the magnet without materially affecting the density thereof as to permit the interrupter to be actuated.
- 70 14. In an electric circuit, the combination with a circuit interrupter, of an electromagnet for holding the interrupter closed, and means energized upon a sudden change in the condition of the circuit and in anticipation of a rush of current for so decreasing
- 75 130
- 80 115
- 85 120
- 90 110
- 95 125
- 100 130
- 105 115
- 110 120
- 115 125

- the holding effect of the flux of the magnet without materially affecting the density thereof as to permit the interrupter to be actuated.
- 5 15. In an electric circuit, the combination with a circuit interrupter, of a magnet and an armature therefor for holding the interrupter closed, and means responsive only to sudden changes in the condition of the circuit for so deflecting the magnetic flux of the magnet from the armature as to decrease the holding effect of the magnet and permit the interrupter to be actuated.
- 10 16. In a direct-current circuit, the combination with a circuit interrupter, of an electromagnetic device for holding the interrupter closed, and means energized from the circuit in anticipation of a rush of current therein for so shifting the flux of the electromagnetic device that the interrupter is permitted to open quickly.
- 15 17. In an electric circuit, the combination with a circuit interrupter, of a magnet and an armature therefor for holding the interrupter closed, and means associated with the armature member and responsive only to sudden changes in the condition of the circuit for so deflecting the magnetic flux of the magnet from the armature as to decrease the holding effect of the magnet and permit the interrupter to be actuated.
- 20 18. In an electric circuit, the combination with a circuit interrupter, of an electromagnetic comprising a stationary magnetizable core member, an armature, a potential winding for actuating the armature to hold the
- interrupter closed, and a winding energized in anticipation of a predetermined flow of current in the circuit for preventing the flux from the potential winding from actuating the armature.
- 25 19. The combination with an electric circuit, of electromagnetic circuit-controlling means and means dependent only upon a quick change of current in the circuit for so shifting the flux of the electromagnetic means as to cause an actuation thereof.
- 30 20. The combination with an electric circuit, of electromagnetic means for controlling the same and means dependent only upon a quick change of current in the circuit for so shifting the flux of the electromagnetic means as to cause an actuation thereof.
- 35 21. The combination with an electric circuit, of electromagnetic circuit-controlling means and means dependent upon the rate of change of current in the circuit for so shifting the flux of the electromagnetic means as to cause an actuation thereof.
- 40 22. The combination with an electric circuit, of electromagnetic circuit-controlling means and means energized in anticipation of a rush of current in the circuit for so shifting the flux of the electromagnetic means as to cause an actuation thereof.

In testimony whereof, we have hereunto subscribed our names this 26th day of Sept., 1918.

CHARLES LE G. FORTESCUE.
FREDERIC C. HANKER.
